CATHODE-RAY TUBE AND THE LIKE

Robert M. Bowie, St. Marys, Pa., assignor to
Hygrade Sylvania Corporation, Salem, Mass., a
corporation of Massachusetts

Original application September 4, 1936, Serial No.
99,384. Divided and this application June 29,
1937, Serial No. 150,906

6 Claims. (Cl. 250—141)

This invention relates to cathode-ray tubes and more particularly to cathode-ray tubes of the composite metal-glass type.

An object of the invention is to provide an improved cathode-ray tube of the type having a composite metal-glass flare portion.

In cathode-ray tubes of the type wherein the main body portion of the envelope is of metal, it is not advisable to locate the usual deflecting plates in the vicinity of the metal part of the tube, particularly where the deflection is to be effected electromagnetically, because of the possible energy loss in the said metal part. However by constructing the neck portion of the envelope of glass or other vitreous material, it is possible to build a highly efficient and accurately controllable cathode-ray tube, wherein the main body portion is of metal. However since the deflecting plates are usually located in the flared end of the neck portion, it is requisite that this flared portion be of comparatively large diameter, especially in the larger tubes where even the reduced end of the metal part of the envelope may be of the order of several inches in diameter. While the reduced end of the metal part of the envelope can, by ordinary methods, be made to very accurate dimensions, the same is not true of the manufacture of the co-operating flared end of the glass neck portion. While methods of flaring a glass tube to a relatively large diameter are well-known, I have found that these methods are not suitable for use in forming the flared portion of the tube neck. Furthermore these usual methods of flaring a glass tube to large diameters, are slow and highly accurate dimensions cannot be produced with sufficient uniformity and reliability to warrant their use in quantity production of large cathode-ray tubes.

Accordingly it is a principal feature of the present invention to provide a composite metal-glass cathode-ray tube envelope, which is suited to quantity production, and wherein the flared neck portion of the tube can be made with a very high degree of accuracy and uniformity.

Another feature relates to the novel organization, arrangement and relative location of parts which constitute an improved composite metal-glass cathode-ray tube envelope.

Other features and advantages not specifically enumerated will be apparent after a consideration of the following detailed descriptions and the appended claims.

In the drawing, Fig. 1 is a schematic sectional view of a device to explain the method of forming certain parts of a cathode-ray tube envelope according to the invention.

Fig. 2 is a sectional view to illustrate another step in the formation of the cathode-ray tube envelope.

Fig. 3 is a view of the completed cathode-ray tube made in accordance with the invention.

Referring more particularly to Fig. 3, the cathode-ray tube envelope is of the composite metal-glass type and comprises a substantially flat end wall 1 of glass or similar vitreous material having its interior face coated with suitable fluorescent material (not shown). The envelope comprises an elongated conical portion 2 of steel or other suitable metal. The neck portion of the envelope comprises a substantially cylindrical glass tubular portion 3 terminating at its left-hand end in an enlarged flare 4. Inasmuch as it is not practical to form a vacuum-tight seal between the metal 2 and the glass 3, there is interposed a frusto-conical ring 5 of a metal which has the same coefficient of expansion as the glass 4. Preferably the flare 4 is of Corning 705 AJ glass, and the ring 5 is of "Kovar" an alloy consisting of approximately 18% cobalt, 28% nickel and 54% iron. After the parts 1 to 5 have been assembled as described hereinbelow, the envelope has mounted therein the usual electrode assembly, and the tube is then exhausted and processed according to known procedure. After the tube has been processed and sealed-off, it may have fastened thereto a contact base 6 with appropriate contact prongs 7.

As will be seen from the foregoing description, the metal portions 2 and 5 are of rigid metal and in order to effect a proper vacuum-tight seal between members 4 and 5 it is necessary that the mouth of the flare 4, be of accurate diameter. I have found that the ordinary methods of flaring a glass tube and uniting it to a metal ring are not suitable for use in cathode-ray tubes of the type described, either because of the time required to effect the proper seal, or because of the lack of reliability or uniformity in the seal. I have also found that by employing a special pressure molding operation it is possible to overcome the above-noted disadvantages, and as a result relatively large composite metal-glass cathode-ray tube envelopes can be made comparatively economically and with accurate dimensions.

Referring to Fig. 1 a description will now be given of the manner of simultaneously forming the flare 4 and sealing it in a vacuum-tight manner to ring 5. In Fig. 1 the numeral 8 represents schematically a suitable mold having a frusto-conical mold cavity terminating at its bottom in a reduced cylindrical cavity. The mouth of the conical cavity is provided with a raised rim 9 for the purposes about to be described. The metal ring 5 is seated on the rim of the mold as shown, so that the lower edge of the frusto-conical portion 10 extends into the mold cavity beyond the rim 9 thus providing a slight clearance between the said edge and the face of the mold cavity. The clamping ring 11 is placed in position to

hold the ring 5 rigidly in place. A "gather" or ball of molten glass preferably at white heat is then allowed to fall into the mold cavity and immediately thereafter the plunger 12 is lowered 5 to force the liquid glass upward until it engages the edge of ring 5 and flows therearound as shown. It will be noted that the head of the plunger 12 is shaped complementary to the mold cavity so that when said plunger is in its lowermost position 10 the molten or liquid glass assumes a frusto-conical shape terminating in a cylindrical cup at its lower end as shown in section in Fig. 1. Preferably the "gather" is heated prior to being dropped into the mold to such a temperature, and preferably the "gather" is of such a mass 15 that when it contacts with the edge of ring 5 it raises the latter to a sufficiently high temperature at which the oxide on the said edge dissolves in the molten glass, it being understood that the said edge has been previously oxidized in any 20 well-known manner. There is thus formed a composite metal-glass assembly consisting of an accurately dimensioned frusto-conical glass part sealed in a vacuum-tight manner to the Kovar 25 ring 5.

After the composite metal-glass assembly has cooled sufficiently in the mold, whereupon it may be removed and annealed in any well known manner. The annealed assembly is mounted in 30 a suitable air-tight jig such for example as shown in Fig. 2 comprising a rotatable head 14 and a clamping ring 15, adapted to be held in place by suitable springs 16. The hub 17 is provided with a passage-way 18 leading to a blowing hose for 35 purposes to be described. With the assembly as shown in Fig. 2 set in rotation, the glass blower then heats the end 20 to soften it, and at the proper instant he blows through passage 18 to blow the end 20 to a bubble which can then be 40 broken off. By means of a carbon rod or paddle the edge 19 is straightened and smoothed to the proper diameter, while the said part 19 is still within the softening flame. A suitable length of glass tubing 3 is then placed in axial alignment 45 with the end 19 and the two are sealed together in the manner well-known in the glass blowing art.

When the joining of the cylindrical glass neck portion 3 has been completed, the clamp 15 is 50 removed and the assembly comprising elements 3, 4 and 5 is united to the metal member 2. Preferably the rim of ring 5 is welded to the reduced end of member 2 to form a vacuum-tight seal therewith. The finished composite metal-glass envelope is then ready to receive the electrode assembly or mount.

It will be understood of course that the glass end 1 may be sealed to the metal member 2 either before or after the union of parts 2 and 5 as 60 above-described. Likewise the parts 2 and 5 may be welded together as a unit prior to sealing thereto the glass flare as above-described. In this latter case the mold will be provided with a suitable clamping member to hold the parts rigidly in place during the pressure on the glass "gather" 65 in the mold as described.

Other modifications may be made in the method described, without departing from the spirit and scope of the invention. For a detailed disclosure of preferred forms of electron guns, control electrodes, and deflecting means that may be 70

used with the tube as described, reference may be had to application Serial No. 95,970, filed August 14, 1936.

This application is a division of application Serial No. 99,384, filed September 4, 1936. 5

What I claim is:

1. A cathode-ray tube having a main funnel-shaped body portion of metal, an elongated cylindrical glass neck joined to a composite glass-metal flare said flare comprising a frusto-conical glass section and a metal sealing ring with a corresponding frusto-conical section, said sealing ring being of a metal different from that of said body portion and sealed to the glass section in a vacuum-tight manner, the parts of said composite flare being preformed and sealed together as a separate unit from the remainder of the tube, a vacuum-tight weld between said ring and the constricted end of said body portion, a glass window sealed in a vacuum-tight manner to the enlarged end of said body portion, and ray deflecting means adjacent the glass section of said composite flare. 10 15 20

2. A cathode-ray tube according to claim 1 in which the glass section of the composite flare and the metal section thereof have substantially the same angular opening. 25

3. A cathode-ray tube according to claim 1 in which the said sealing ring has a frusto-conical flare portion where it is sealed to the corresponding frusto-conical glass section of the composite flare. 30

4. A cathode-ray tube according to claim 1 in which said main metal body portion has a cylindrical collar at its narrow end and said sealing ring has a cylindrical portion welded to said collar and a frusto-conical portion sealed into the corresponding frusto-conical glass section of the composite flare. 35

5. A composite metal-glass flare unit for joining an elongated glass neck to the metal body section of a cathode-ray tube which glass neck has a different coefficient of expansion from that of said metal body section comprising a metal ring having a preformed frusto-conical section sealed in a vacuum-tight manner to a preformed corresponding frusto-conical glass section, said ring and glass section being formed as a separate unit and having substantially the same expansion coefficient. 40 45 50

6. A cathode-ray tube having a main body portion of metal, an elongated cylindrical glass neck joined to a composite glass-metal flare said flare comprising a frusto-conical glass section and a metal sealing ring with a corresponding frusto-conical section, said sealing ring being of a metal different from that of said body portion but having the same expansion coefficient as said glass section, whereby it is sealed to the glass section in a vacuum-tight manner, the parts of said composite flare being preformed and sealed together as a separate unit from said cylindrical glass neck and the remainder of the tube, a vacuum-tight weld between said ring and the constricted end of said body portion, a closure member sealed in a vacuum-tight manner to the enlarged end of said body portion, and ray deflecting means adjacent the glass section of said composite flare. 55 60 65 70
